Term of patent 14 years

Int. Cl. D7—04

U.S. Cl. D81—25

Fig. 1.

Fig. 2.

FIGURE 1 is a top plan view of a burner grate or the like, according to our new and ornamental design.

FIGURE 2 is an elevational view of the burner grate or the like of FIGURE 1 taken approximately on the plane of the line 2—2 of FIGURE 1.

FIGURE 3 is a bottom plan view of the burner grate or the like of FIGURE 1 turned about 60° from its position in FIGURE 1.

FIGURE 4 is an elevational view of the burner grate or the like similar to FIGURE 2 but rotated about 60° clockwise.

In FIGURE 2 a portion is broken away to reveal an otherwise hidden part of the burner grate. The revealed part is the same for each of the radially extending supports.

We claim:

The ornamental design for a burner grate or the like, substantially as shown and described.
